UNITED STATES PATENT OFFICE.

JOHN J. VOGLER, OF DOUGLASTON, NEW YORK, ASSIGNOR TO ALFRED H. SMITH CO. INC., OF NEW YORK, N. Y., A CORPORATION OF NEW YORK.

DESIGN FOR A PERFUME BOTTLE.

Application filed December 22, 1922. Serial No. 4,682. Term of patent 3½ years.

To all whom it may concern:

Be it known that I, JOHN J. VOGLER, a citizen of the United States, residing at Douglaston, in the county of Queens and State of New York, have invented a new, original, and ornamental Design for Perfume Bottles, of which the following is a specification, reference being had to the accompanying drawing forming part thereof.

Fig. 1 is a front elevation; and

Fig. 2 is a side elevation.

In the design hereof the upper or cap portion of the bottle and the body or base are of contrasting color.

I claim:

The ornamental design for a perfume bottle as shown.

JOHN J. VOGLER.
